RADIO RECEIVER CONTROL

Jason A. Chadkin, Brooklyn, N. Y., assignor to
 Radio Corporation of America, a corporation
 of Delaware

Application June 3, 1933, Serial No. 674,173

6 Claims. (Cl. 250—20)

This invention relates to a radio receiver control and more especially to such a control which is arranged to be operated by a clock device.

It is an object of the invention to provide such a control in which an alarm clock or similar device may be arranged to put into operation a radio receiver and thereby cause it to reproduce broadcast speech or music.

A further object of the invention is to provide an ordinary alarm clock with certain insulated connections whereby certain parts of it may be used as a switch mechanism to close a circuit to a radio receiver.

A still further object of the invention is to improve generally the efficiency of a time control signal device and to permit the same to be readily and cheaply constructed by means of component parts which are readily available on the market. Other objects of the invention will be come apparent to those skilled in the art as the description thereof proceeds.

For a better understanding of the invention reference is made to the accompanying drawing in which,

25 Figure 1 is a schematic circuit arrangement showing how the several parts of the device may be connected;

Figure 2 is a view of the alarm device showing in more detail the circuit connections thereto; 30 and,

Figure 3 is a cross sectional view of a four wire cable which may be used for making the connections.

Referring to Figure 1 of the drawing reference 35 numeral 32 denotes a complete radio receiver including a loudspeaker LS, the entire receiver and loudspeaker being mounted in a suitable cabinet 25. The radio receiver may be of the tuned radio frequency type or of the superheterodyne type 40 and have the usual tuning means whereby any desired broadcasting station operating in the present broadcasting range may be tuned in. The receiver may be, for example, of the type disclosed in Miessner Patent No. 1,720,914 and 45 may include the transformer, rectifier and filter circuit of said patent for supplying the necessary power to the tubes and loudspeaker thereof. As shown in said patent the primary P of the power transformer is connected to a plug 29 adapted to 50 be screwed into a wall socket through a flexible two wire cable 30.

Included in series in this power supply circuit is a switch blade S which in its closed position connects the switch terminals 27 and 28 to energize the circuits within the receiver and cause

the loudspeaker thereof to operate when a desired station is tuned in.

Mounted in a separate cabinet 21 is a separate loudspeaker 22 and an alarm clock 20. The alarm clock has the standard clock mechanism and control device whereby the operator thereof may set it to ring at any desired time. Both the loudspeakers mentioned are preferably of the electro-magnetic type, the plus terminals of their operating coils being denoted by numeral 23 and 10 their minus terminals by numeral 24. These terminals are connected together as shown by insulated conductor 25 and 26. As shown in Figure 1, one end of a conductor 18 is connected to switch terminal 27 and its opposite end connected 15 in any preferred manner to the bell 15 of the alarm clock. The other switch terminal 28 is connected by a conductor 19 to the metallic operating member 8 which carries the bell clapper 14. The insulated wires which connect the mechanism within cabinet 21 to the radio receiver may 20 all be arranged within an insulated covering 31 which may be of braided fabric or similar material which is readily flexible, so that the connections between the alarm device and the radio 25 receiver may be laid flat on the floor of the room and be small and inconspicuous as shown in Fig. 3.

As shown more in detail in Figure 2 the alarm 30 mechanism of the clock is represented diagrammatically by numeral 13 and is provided with the usual operating lever 12 having a pin 11 secured at its end at right angles to its length, the pin 11 serving to oscillate back and forth in a slot 10 in the metallic spring member 8 which carries 35 the bell clapper 14. This alarm operating mechanism is all mounted on the frame member 1 of the alarm clock and is of standard and well known construction. For the purposes of this invention, however, it is necessary, where the frame 40 member 1 is made of metal to insulate member 8 therefrom. For this purpose an upstanding lug 7 of insulation material may be secured to member 1 by any preferred means not shown and member 8 secured to said lug by screws 9 as 45 shown.

I also prefer to insulate the bell 15 of the clock from frame 1 by providing an upstanding lug 17 of insulation material which may be secured to member 1 by any preferred means not shown. A 50 pillar 16 which serves to support the bell 15 may be secured to member 17 by any preferred means such as the screw 33. The usual slide device for shutting off the alarm is also shown and comprises a slide member 3 having an elongated slot 55

4 through which passes a screw 5. This screw may be screwed into a member 2 of insulation material, member 2 being secured to the frame 1 by any preferred means not shown. The slide 3 is tapered at its right end to engage member 8 and press it to the right thus causing the clapper 14 to rest firmly against bell 15 and stop the alarm. Slide member 3 has the usual operating handle 6 at one end and, if member 3 is made of metal, I prefer to make the operating knob 6 of insulation material so that the operator will not be subject to the voltage of the current supplied. As shown the conductor 18 may be connected near the top of member 8 in any preferred manner and conductor 19 connected to bell 15.

In the operation of the device the operator may tune in a desired broadcasting station in the evening before retiring and then open switch 5 of the receiver. This will cause the circuits of the 20 receiver to be de-energized and no sound will come from the speaker LS. The cabinet 21 may be placed near the bed of the user and in the evening he sets the alarm to ring at any desired hour in the usual manner. Upon being awakened 25 by the alarm, when the operator shuts off the alarm by moving slide 3 to the right, it will be seen that the clapper 14 is held in contact with bell 15 thereby closing the power supply circuit to the receiver whereupon the operator will hear 30 reproduced from speaker 22 the speech or music which is being broadcasted from the station to which his receiver 32 is tuned in. If this program consists of announcements of exercises, it will readily be seen that the described arrangement 35 permits the user of this device to engage in athletic exercises immediately after being awakened in the morning by his alarm clock. When the alarm is operating, the operator receives sound waves consisting largely of a single 40 note or frequency and after stopping the alarm he receives sound waves representing music or voice frequencies from speaker 22 which frequencies may cover a fairly wide band.

It will be understood that the radio receiver 45 32 may be located in the operator's bedroom in which the cabinet 21 is placed or it may be located in another room of the dwelling and the cable 31 connecting the two devices may be any reasonable length up to about fifty feet.

50 While I have shown an alarm clock as the means for giving the alarm, I may employ instead thereof a loudspeaker which is energized to give a constant frequency thereon such, for example, as the speaker 58 disclosed in application filed 55 in the name of H. J. Nelson and B. S. Franklin, Serial No. 470,000, filed July 23, 1930. When using such a speaker the operator will be awakened by a tone of substantially one frequency and upon shutting off this tone he will hear the music 60 or voice frequencies being received through the loudspeaker 22.

Having described my invention what I desire to secure by Letters Patent is:—

65 1. In combination in a signalling system, an alarm clock having fixed and movable operating members, time controlled means for causing said

movable member to strike said fixed member to thereby produce sound waves, a manually adjustable member arranged to engage said movable member and retain it in contact with said fixed member, a radio receiver including a loudspeaker and a power supply circuit and a pair of leads connecting said fixed and movable members in series in said power supply circuit, whereby said radio receiver is energized when said manually adjustable member is moved into engagement with said movable member. 10

2. In combination in a signalling system, a radio receiver including a loudspeaker, a power supply circuit arranged to energize said receiver and including a switch having two terminals, an alarm device having a stationary and a movable member, time controlled means for causing said movable member to strike said stationary member to produce sound waves and a pair of electrical conductors having one end connected to said switch terminals and their opposite end to said movable and stationary members whereby said power supply circuit is closed when said movable member is in contact with said stationary member and manually operable means for retaining 25 said members in contact.

3. In combination in a signalling system, a loudspeaker, a circuit for supplying energizing currents to said speaker, an alarm device located at a distance from said speaker and including a bell and a movable clapper member, time controlled means for causing said clapper member to strike said bell repeatedly and a pair of leads having their ends connected to said energizing circuit and their opposite ends to said bell and clapper respectively, whereby said energizing circuit is closed when said clapper and bell are in contact. 30

4. The combination defined in the preceding claim in which said clapper member and bell are insulated from the frame of said alarm device. 40

5. In combination, a casing, an alarm clock having a pair of separable conducting members and a loudspeaker mounted in said casing, means for generating audio frequency currents located 45 at a point remote from said casing, a power supply circuit arranged to energize said means including a pair of conductors having their ends connected to the conducting members of said alarm clock. 50

6. In combination, a casing, a time controlled sound producing device and a sound reproducer mounted in said casing, said time controlled device including a pair of separable conducting members and said sound reproducer having a pair of input terminals, a radio receiver mounted at a point remote from said casing and comprising a sound reproducer having a pair of input terminals, a pair of leads connecting the input terminals of said sound reproducer together and a power supply circuit for said radio receiver including a pair of conductors having their adjacent ends connected to said separable conducting members. 55 60 65
